UNITED STATES PATENT OFFICE.

FRANK H. BACHELDER, OF ORANGE, MASSACHUSETTS.

NEEDLE AND SHUTTLE SELLING-CABINET.

1,369,213.

Specification of Letters Patent. Patented Feb. 22, 1921.

Application filed April 27, 1920. Serial No. 377,058.

To all whom it may concern:

Be it known that I, FRANK H. BACHELDER, a citizen of the United States, residing at Orange, in the county of Franklin and State 5 of Massachusetts, have invented certain new and useful Improvements in Needle and Shuttle Selling-Cabinets, of which the following is a specification, reference being had therein to the accompanying drawing.

10 This invention relates to improvements in needle and shuttle selling cabinets, and is for the purpose of providing a cabinet adapted to contain packages of needles of different sizes and for different machines, 15 and also shuttles for the different machines, whereby the salesmen can quickly and accurately obtain the needle or shuttle desired by the purchaser.

20 The primary object of my invention is to provide a cabinet having a revoluble shaft carrying a plurality of radiating needle package carrying pockets and a plurality of shuttle compartments combined with means for rotating the shaft, and a pointer adapted 25 to stop the shaft at the proper point to position the pocket carrying the desired needle or shuttle, where they can be removed through an opening in the cabinet case.

30 Further objects of the invention will appear from the following description and disclosure.

In the accompanying drawings:

35 Figure 1 is a perspective view of a needle and shuttle cabinet embodying my invention.

Fig. 2 is an enlarged perspective view of a portion of the under side of the top of the cabinet, showing the manner of supporting the sliding pointer.

40 Fig. 3 is an enlarged top plan view of the indicating plate.

Fig. 4 is a vertical transverse sectional view on the line 4—4, of Fig. 1.

45 Fig. 5 is a horizontal sectional view on the line 5—5 of Fig. 4.

Fig. 6 is a horizontal sectional view on the line 6—6 of Fig. 4.

Fig. 7 is an enlarged sectional view of the sliding pointer.

50 Fig. 8 is a top plan view of the top of the member carrying the needle package pockets, showing the spiral arrangement of the notched stops carried thereby.

In carrying out my invention, I provide 55 a suitable case which, in the form here

shown, comprises a rectangular bottom portion 1, and a circular or drum portion 2, mounted on the top of the rectangular box-like portion 1.

A revoluble shaft 3 has its upper end in 60 a suitable bearing in the top 4, of the circular portion 2, and its lower end 5, stepped in a suitable bearing 6. A beveled gear 7 is secured to the shaft 3, just above the top 8 of the rectangular portion 2, and a horizontal operating shaft 9 is journaled in suitable bearings 10, and carries a beveled gear 11, which meshes with the gear 7. The outer end of the shaft 9 projects beyond the cabinet case, as shown in Figs. 1 and 4, and is 65 provided with a suitable knurled wheel 12. By this means the shaft 3 is rotated from the outside of the cabinet in either direction.

A circular member 13 is secured to the 70 shaft 3, at the points 14, and this circular member carries a plurality of radiating pockets 15, which are to receive packages 16 of needles arranged flat-wise therein. The circular portion 2 of the cabinet case is provided with a vertical opening 17, 75 through which the packages of needles may be removed from their pockets. The pockets have outer open ends and are caused to register with the openings 17, so that the desired package of needles may be removed 80 therefrom.

For the purpose of causing the pocket containing the desired package of needles to 85 stop at the opening 17, I provide a pointer and stop arrangement, which will automatically stop the member 13, with its needle pockets at the opening 17, as it is being rotated through the wheel 12 and shaft 9, as 90 before described.

The pointer and stop mechanism includes 95 the top 18 of the member 3, provided with a plurality of triangular-shaped members 19, which have stop notches 20, at their apex, as shown clearly in Figs. 2 and 4. These notched stop members 19 are arranged substantially as shown in Fig. 8. A pointer member 21 slides back and forth on parallel rods 22, which are secured to the top member 4 of the circular part 2, as shown in Fig. 2. This sliding member or head 21 carries 100 a knurled member 23, which is provided with oppositely extending pointers 24. Secured to the top of the circular portion 2, is an indicator plate 25. This plate has a longitudinal slot 26, in which the stem 27 of 105

the pointer member 23 moves. This indicator plate 25 has at one side of the slot notations designating different kinds of sewing machines, and their numbers of needles, 5 and above the needle notations appears the word "Needles." On the other side of the slot 26 is designated the names of different sewing machines, and above this designation is the word "Shuttles." The sliding head 21, 10 carries a spring detent 27, which is adapted to engage in the notches of the stop members 19. This detent 27 has a slot 28, through which a pin 29 passes, the upper end of the 15 detent carrying a plunger head, which is depressed by a suitable spring 31, located between the stem 27 and the plunger, as clearly shown in Fig. 7.

Located within the rectangular box-like portion 2 is a circular shuttle carrying member 32, which is provided with a plurality of radiating shuttle carrying pockets 33. This shuttle pocket carrying member 32 is attached to and supported by the lower end of the shaft through the medium of a suitable 25 flanged collar 34, so that the member 32 and its shuttle pockets are rotated when the shaft 3 is rotated through the medium of the wheel 12, shaft 9 and gears 7 and 11.

For the purpose of preventing the needle 30 packages 16 from being thrown out by the centrifugal action, if the device is rotated rapidly, I provide each pocket 15 with a suitable spring 15', which extends the height of the pocket and serves to cause a slight 35 frictional tension on the packages of needles to prevent them from being thrown out by centrifugal force.

For the purpose of permitting access to the shuttle pockets 33, the edge of the rectangular box-like portion 1 is provided with a door 35, hinged at its lower end as at 36, 40 and this door extends into the top of the rectangular portion 1 and the circular portion 2, as shown at 37, whereby when the door is 45 moved outward by its handle 38, access to the shuttle pockets 33 is permitted through the side and top of the rectangular portion 1, and the lower edge of the circular portion 2.

50 In operation when a certain package of needles is desired for a certain sewing machine, the salesman moves the pointer member 23 until its pointer 24 is opposite the indication on the plate 25 of the needle desired. The wheel 12 is then rotated and the 55 spring detent 27 will engage the proper stop member 19 to cause the proper needle pocket 15 to register with the opening 17 of the circular case 2. In this manner the proper pocket is automatically caused to register with the exit opening 17.

Likewise when it is desired to have any 60 desired shuttle, the pointer 24' is put opposite the machine for which the shuttle is desired and the detent 27 of the pointer will

engage the proper stop member 19 to cause the proper shuttle pocket 33 to register with the door 35.

By moving the pointer member 23 to the "neutral" point of the indicating plate 25, 70 the shaft 3 and its connecting parts can be freely rotated, as may be desired.

By means of a selling cabinet of this type, the salesman can very quickly turn to the desired package of needles or shuttles, thus 75 saving time as well as making the transaction simple and accurate.

Having thus described my invention what I claim and desire to secure by Letters Patent is:

80

1. A selling cabinet of the type described, comprising a case having therein upper and lower rotating compartments, the lower compartment carrying a plurality of radially arranged shuttle pockets, the upper compartment carrying a plurality of radially arranged needle carrying pockets, an article retaining spring friction member in the needle carrying pockets, separate exit openings in the case for the upper and lower 90 compartments, an article pocket indicator plate and pointer at outside of the case co-operating with a plurality of stop members spirally arranged on top of the upper rotating compartment, whereby the pocket indicated is caused to stop in registered relation to the exit opening in the case, and means for rotating the said pocket carrying compartment.

95

2. A selling cabinet of the type described, 100 comprising a case, having an exit opening therein, a rotatable shaft within the case, operative means therefor extending to the outer side of the case, an indicator plate on the top of the case arranged radially to the case, a pointer co-operating with the plate and moving radially in respect to the case, a rotating member within the case connected with the shaft and carrying a plurality of radiating pockets with open outer ends, a 105 plurality of stop members spirally arranged on the top of the radiating member and co-operating with the pointer, whereby the pocket indicated by the pointer is caused to stop in registered relation to the exit opening in the case.

110

3. A selling cabinet of the type described, having a vertically arranged exit opening therein, a rotatable shaft within the case, operating means therefor extending to the outer side of the case, an indicator plate on the top of the case arranged radially to the case, a pointer arranged to slide radially of the case and longitudinally of the plate, a rotating member within the case connected to the shaft and carrying a plurality of radiating pockets with open outer ends, spring friction article retaining members within the pockets, a plurality of stop members spirally arranged on the top of the rotating 115

120

125

130

135

member, the stop member notched to receive a downwardly extending end of the pointer, whereby the pocket indicated by the pointer is caused to stop in registered position to 5 the exit opening in the case.

4. A selling cabinet of the type described, comprising a case having an exit opening, a rotatable member within the case and having operative means extending outside of 10 the case, said rotatable member having a plurality of radially arranged pockets with open ends, an indicator plate having a radially arranged slot, a pointer co-acting with the plate and with notched lugs spirally arranged on the top of the rotating pocket carrying member to cause the pocket carrying member to stop with the pocket indicated by the pointer in registered relation with the exit opening in the case.
- 20 5. A selling cabinet of the type described, comprising a circular case having in its vertical wall an exit opening, a circular arranged member within the case carrying a plurality of radially arranged pockets having 25 open outer ends, an indicator plate on the top of the case having a radially arranged slot with notations at its side, a pointer member movable in the slot, the top of the pocket carrying member having 30 notched stop members spirally arranged to coöperate with the pointer, the pointer and stops having spring detent engagement, and

means for rotating the pocket carrying member, for the purpose described.

6. A selling cabinet of the type described, 35 comprising a case having an exit opening, a rotating member in the case having a plurality of pockets adapted to register with the exit opening, means for rotating said member, the rotating member having a plurality of spirally arranged stops, and an externally operated radially movable member coöperating with the stops, for the purpose described.

7. A selling cabinet of the type described, 45 comprising a case having a lower shuttle compartment and an upper needle case compartment, a rotatable member in the lower compartment carrying a plurality of radially arranged shuttle pockets, and a rotatable member in the upper part of the case carrying a plurality of radially arranged needle carrying pockets, the upper part of the case having an exit opening and the lower part of the case having an exit opening 55 thereunder, an indicator plate and a pointer coöperating to cause the pocket carrying members to stop with the pocket registered with said opening indicated by the pointer, and means for rotating the said 60 pocket carrying members.

In testimony whereof I hereunto affix my signature.

FRANK H. BACHELDER.
